UNITED STATES PATENT OFFICE

1,999,819

FLOORING OR LIKE AGGREGATE AND UNIT
FOR CONSTRUCTION OF THE SAME

Eugène Germain Paul Mopin, Paris, France

Application September 8, 1933, Serial No. 688,594
In France November 17, 1932

6 Claims. (Cl. 72—66)

The present invention relates to flooring or like aggregates, and has for its object to provide a flooring of a reduced weight and of an easy mounting.

5 According to the invention the flooring consists of a series of concrete units in the form of slabs which are prepared in advance and are laid in the transverse position, at their opposite ends, upon auxiliary concrete units which are prepared in advance and are mounted in the longitudinal position in such manner that they will rest upon the lower flanges of metallic beams.

10 According to another feature of the invention, the reinforcing members of the main units forming the slabs extend from the ends of the latter and are bent over the flanges of the metallic beams, or are embedded in the concrete which is filled in on the spot and covers the beams at a point between the longitudinal elements.

15 The invention further relates, by way of new manufactured products, to the units forming the slabs and to the said longitudinal units, and has for its other object to provide units which are so arranged as to comprise simple supporting surfaces at their ends, by which they can be assembled and definitely put in place in a ready manner and at a small expense.

20 The slabs preferably consist of vibrated concrete, and thus their thickness can be reduced, while at the same time their strength is increased.

25 They are provided on their lower side, near the ends, with ribs adapted to make contact with the edges of the longitudinal units, when placed in position, and also at the edges with ribs for containing the traction bars and for forming joints for filling on the spot, and further, with intermediate longitudinal and transverse ribs.

30 The upper side of each unit slab may remain in the rough state, and may thus receive any suitable facings, by the known means, after the slab has been laid and secured in position.

35 The upper side of the slab may also receive its facing during its manufacture at the plant, while the concrete is under the vibration treatment.

40 In this case, the facing may consist of a magnesia product, granito, mosaic, or the like, which is placed in the body of the concrete and is vibrated therein before the setting of the concrete, thus providing a completely finished flooring slab which requires no further addition nor facing.

45 Herein, the upper surfaces of the concrete which covers the beams, as well as the transverse joints between the slabs, are given a surface treat-

ment on the spot, thus affording, in combination with the surface of the slab, any suitable appearance and design, for instance a panelling separated by bands.

50 On the other hand, longitudinal or transverse grooves may be formed on the upper side of each slab, or of certain slabs, for instance adjacent the lower ribs, so as to complete the desired visible panelling.

55 Each longitudinal unit which rests upon one of the beams, preferably consists of vibrated concrete. Its edges are bevelled in order that it may fit at the bottom upon the slope of the lower flange of the beam, and at the top into the angle between the rib and the lower side of the end part of the slab which it serves to support.

60 In this unit are formed, during the moulding process, one or more notches which will give passage to wood strips adapted to receive the ceiling.

65 The entire flooring produced according to the invention, due to its construction in vibrated reinforced concrete of great strength, affords unit parts of reduced thickness, representing a greatly reduced weight, which is only about one-third of the weight of the current flooring.

70 It is very simply mounted, and can be rapidly placed in position. The said flooring, with or without an upper coating which is formed in one with the main body, can be obtained at a very reduced cost, and it also represents a great saving in the construction of walls, foundations and framework, in the buildings in which it is employed.

75 Further characteristics of the invention will be set forth in the following description.

80 In the accompanying drawing, which is given solely by way of example:

85 Fig. 1 is a cross-section of a flooring construction, in conformity to the invention, which consists of the above-mentioned parts.

90 Fig. 2 is a lengthwise section of the same, parallel with the beams, on the line 2—2 of Fig. 1.

95 Fig. 3 is a bottom view of a unit slab.

100 Fig. 4 is a top view of a flooring construction, showing an optional arrangement of panelling.

105 In the form of construction herein represented, the flooring is formed, in each span situated between two consecutive beams 1 and 1^a, of a set of unit slabs A (Fig. 1) which are juxtaposed in the direction of the length of the beams. Each unit A has a suitable length l or l' (Fig. 2).

110 Each unit slab A rests at 2 (Fig. 1) upon the edges of two longitudinal members 3, and each of the latter rests at 4 upon the lower flange of one of the beams 1 or 1^a. The longitudinal spaces

between the members 3 and the beams 1—1^a are filled with concrete 5 in order to assure the preservation of the beams, to increase their moment of inertia, and to provide an additional support 5 for the ends of the slabs.

In the present construction, each unit A consists of an upper horizontal slab 6 having on its lower side suitable transverse end ribs 7 adapted to maintain the members 3, and longitudinal 10 ribs 8 comprising a bevelled rabbet on the upper side of the unit A in order to form a recess which is to be filled on the spot with cement, to provide for the formation of a joint 9 (Fig. 2). The slab 6 is further provided on its lower side with 15 intermediate ribs 10 in the longitudinal position and 11 in transverse position, reinforcing members being arranged in said ribs.

The upper slab 6 may be left rough or may receive before it is mounted, a facing 12 of suitable material such as a magnesia product, granito, mosaic or the like. The facing 12 can be formed during the moulding process, and may be vibrated, together with the concrete body, as disclosed in applicant's French Patent No. 717,465 of May 25 21st 1931, thus forming an integral part of the unit piece.

The slab 6 may comprise grooves or rabbets 13 (Figs. 1 and 4) adapted to receive a filling of mosaic or the like, thus forming a suitable 30 panelling.

As above stated, the transverse joints 9 between the slabs and the upper surface 14 of the concrete 5 covering the beams 1—1^a, are treated on the spot in such manner as to produce any 35 suitable appearance or design in combination with the upper surface of the slabs.

Obviously, if the slabs 6 are mounted in the rough state, the whole flooring will be given a general facing 16, as shown to the right of Figs. 40 1 and 2.

The slab A is provided with reinforcing members 17 which extend from its ends and are bent over the flanges of the beams 1—1^a, or they may be embedded in the concrete 5 (Fig. 1) which 45 fills the spaces next the beams.

The longitudinal members 3 supporting the slabs A may have any suitable length, and this length may correspond to the spacing between the strips 18 which are adapted to receive the 50 ceiling 19, or it may exceed this spacing, and in such case the members 3 will be cut out in order to give passage to the said strips.

The slabs A may have any length, width and thickness, to correspond to the spacing of the 55 beams 1—1^a, and may comprise one or more longitudinal and transverse ribs as well as reinforcing members, according to the span and the load.

The spaces between the ribs of the slabs A may 60 be filled with cellular concrete or the like, in order to improve the non-conducting and the sound-proof qualities of the flooring.

The flooring in conformity to the invention offers numerous advantages which represent a 65 great reduction in cost, due to the elimination of all moulding on the spot, as well as to the

great facility of handling, mounting and placing in position which results from the reduced weight of the units, also to the reduction of useless weight, which greatly reduces the amount of the metallic framework, and the size of the walls, 5 foundations, and the like, and to the immediate obtainment of the facings of magnesia products, granito, mosaic, etc., without any subsequent additions or operations, save for the filling of the joints 5 and 9 to form the panelling. 10

Obviously, the invention is not limited to the forms of construction herein described and represented, which are given solely by way of example.

Having now described my invention what I claim as new and desire to secure by Letters 15 Patent is:

1. A flooring construction comprising spaced flanged beams, longitudinal concrete units resting upon the lower flanges of said beams, transverse concrete slabs resting at their ends upon 20 said units and provided with grooves in their sides and a filling joint in the space formed by the grooves of two adjacent slabs.

2. In a flooring or like construction a number of metallic flanged and parallel beams, a series of 25 slabs disposed therebetween, preformed and provided with reinforcements protruding at their ends for the purpose of positively connecting said slabs with the upper flanges of said beams, and further preformed, inclined and substantially flat 30 concrete elements carried longitudinally along the beams and resting upon the lower flanges of said beams for the purpose of supporting said slabs, said inclined flat elements forming together with the edges of the slabs hollow chambers, surrounding 35 said beams and subsequently filled with concrete.

3. A longitudinal substantially flat element for use in the construction according to claim 2 having bevelled upper and lower edges in order to 40 afford a suitable contact between these edges and the metallic beams upon which they rest and the transverse slabs they are adapted to support.

4. A flooring construction according to claim 2, wherein said slabs are provided at their upper 45 side with grooves adapted to receive facings which form panelling bands.

5. A flooring construction comprising parallel flanged beams, transverse spaced strips carried by said beams, longitudinal substantially flat concrete units resting upon the lower flanges of said beams and provided with notches giving passage to said strips, and transverse concrete slabs resting at their ends upon said units said slabs being provided with reinforcements protruding at their 55 ends for the purpose of connecting said slabs with the upper part of said beams.

6. A concrete slab for the construction of a floor or the like according to claim 2 comprising bearing surfaces adapted to make contact with 60 inclined elements upon which it rests, provided with reinforcements protruding at its ends and preferably comprising on its upper face a facing mounted during the moulding of said slab and the vibration of concrete.

EUGÈNE GERMAIN PAUL MOPIN.
